Application March 29, 1939, Serial No. 264,693

4 Claims. (Cl. 260—671)

This invention relates to an improved process for manufacturing aromatic hydrocarbons, and more particularly to a process in which benzene derivatives containing side chains are produced.

Various processes are known for the production of aromatic hydrocarbons from non-aromatic hydrocarbons by subjecting the latter to various types of thermal treatment. In such operations the aromatic hydrocarbons are formed to a substantial extent by the polymerization or interaction of other hydrocarbons such as olefins, or by dehydrogenation and cyclization.

When oil vapors are cracked in the vapor phase, the cracking results in the formation of gasoline, the percent formed being roughly proportional to the time of digestion during the earlier stages of cracking. The gasoline will contain 50% or more of olefins; 5% to 20% of aromatics, depending on the digestion temperature and the nature of the charging oil; and the balance will be comprised of naphthenes and paraffines. The chemical composition of the gasoline will remain substantially constant during the earlier stages of the cracking, that is, there will be very little variation in the composition at say 5% gasoline or at 25% gasoline formation in a single pass. However, if the digestion is continued long enough, exothermic reactions take place which result in an increase in the proportion of aromatics in the gasoline fraction, with a reduction in the proportion of unsaturates and other constituents. This exothermic reaction can be stopped at any desired point so as to obtain a product of any desired aromatic content. However, the exothermic reaction proceeds with the production of excessive amounts of fixed gas, and the greater the percentage of aromatics in the gasoline, the greater is the gas loss. As an example of such a process, a hydrocarbon oil such as naphtha, kerosene, or gas oil, is heated and vaporized, and the resulting vapors subjected to a long time thermal conversion treatment at temperatures of about 950° F. to 1050° F. at a pressure of from 200 to 500 lbs. per square inch. The original charging stock is converted into a gasoline product containing from 40% to about 90% of aromatic hydrocarbons, depending upon the length of the reaction period, with a gas loss of from 30% to 40% of the original charging stock.

The process of the present invention is more particularly an improvement on this prior process for manufacturing aromatic hydrocarbons. The present invention contemplates stopping the high temperature exothermic reaction when a

moderate proportion of aromatics are formed, (say 30% to 40% in the gasoline fraction), and allowing the reaction involving further aromatic formation to take place at a lower temperature in the presence of a catalyst under conditions which result in the formation of appreciably smaller quantities of fixed gas.

Therefore, the primary object of the present invention is to provide an improved process for the manufacture of aromatic hydrocarbons, and more particularly aromatic compounds containing side chains, and at the same time avoid the excessive loss usually encountered in known purely thermal processes of the type referred to.

15 A further object of the invention is to provide an improved process for the manufacture of side chain cyclic and aromatic hydrocarbons from mineral oils in order to provide such hydrocarbons for various purposes such as solvents, chemicals, and compounds, for use as blending agents to increase the anti-knock value of relatively poor gasolines.

Accordingly, the improved process of the present invention comprises the steps of subjecting a 20 hydrocarbon oil such as a gas oil, kerosene or naphtha, to a thermal conversion operation preferably while flowing in a confined stream of restricted cross section through a long heated pipe coil, heating the oil to a temperature of 25 from about 980° to 1020° F. at a pressure of approximately 250 lbs. per square inch, maintaining the hydrocarbon oil at approximately said 30 temperature or slightly higher, for a period of time sufficient to convert the oil into a product containing a substantial proportion of condensable constituents boiling below about 400° F., which contains approximately 35% of aromatic hydrocarbons, and approximately 45% of olefinic type hydrocarbons, thereafter subjecting the 35 vaporized products from the heating operation, and particularly the vapors including constituents boiling below approximately 500° F., to the action of an alkylation and/or cyclization catalyst while maintaining the hydrocarbon in vapor state, whereby the olefinic hydrocarbons contained in the mixture are reacted with the aromatic hydrocarbons to form side chain alkylated cyclic and aromatic compounds, and further aromatic formation from unsaturates takes 40 place. Various catalysts may be used for effecting these reactions, such as phosphoric acid, phosphorus pentoxide, aluminum chloride, barium chloride, boron halide, the lower oxides or sulfides of chromium, cobalt, molybdenum, 45 uranium and tungsten, and a silica gel reaction 50

product with phosphoric acid. The catalytic reaction is preferably carried out at a temperature of approximately 700° F. and at a pressure of approximately 50 to 200 lbs. per square inch.

Other features, objects and advantages of the improved process of the present invention will be apparent to those skilled in the art from the following more detailed description thereof, taken in connection with the accompanying drawings in which:

Fig. 1 is a more or less conventional diagrammatic elevational view of assembled apparatus elements particularly adapted for carrying out the improved process.

Fig. 2 is a view similar to Fig. 1 showing a modification of apparatus for carrying out a modified form of the improved process of the present invention.

Fig. 3 is an enlarged broken sectional view illustrating a form of rotary valve structure shown in Fig. 2 of the drawings.

Referring to Fig. 1 of the drawings, the crude hydrocarbon to be used for the manufacture of aromatic hydrocarbons in accordance with the process of the present invention, is introduced into the apparatus under pressure by means of a pump (not shown) through a line 2, and preferably passed through a plurality of heating tube banks 4, 6, 8 and 10 mounted in a pipe still furnace 12 which may be of usual and well-known type and structure. The oil stock in passing through the tube banks 4 and 6 is preferably heated to a temperature from about 920° to 950° F. and thereafter heated in the tube banks 8 and 10 to a temperature of from 980° to about 1020° F. at which temperature the highly heated products are discharged through a transfer line 14 into the lower portion of an enlarged vertical reaction chamber 16.

The tube banks 8 and 10, or tube bank 10, is preferably of sufficient length to give a substantial period of reaction time for breaking up and converting substantial proportions of the hydrocarbons into products boiling below 450° F. The highly heated products discharged into the reaction chamber 16 are subjected to a relatively long time soaking reaction which is preferably exothermic in nature, so that the temperature actually rises in the chamber to a point of from 1000 to 1070° F. at the top of the chamber where the vapors are discharged through a line 18. Some of the exothermic reaction may take place in the tube bank 10 and is continued in the chamber 16 which is preferably heavily insulated. By the time the conversion products reach the top of the chamber 16, they preferably contain approximately 35% of aromatic hydrocarbons and 45% of olefinic hydrocarbons in the fraction boiling below temperatures of from 400° to 450° F. Such a fraction suitable for subsequent catalytic conversion may contain from approximately 35% to approximately 55% of olefinic hydrocarbons and from approximately 30% to approximately 45% of aromatic hydrocarbons.

As the highly heated hydrocarbons discharge through the line 18, their temperature is preferably reduced instantaneously to a point within the range of approximately 600° to 800° F. by introducing into the discharging vapors a fluid cooling medium from a valved line 20. The resulting mixture passes on through a valved line 22 into a vapor separator 24 where any condensed or unvaporized materials are separated from the hydrocarbon vapors.

In carrying out the reaction in the chamber 16,

some free carbon of the nature of carbon black is usually formed in the reaction chamber. Where this occurs, it may be readily blown from the chamber through a valved line 26. During the operation the liquid collected in the vapor separator 24 is preferably withdrawn through a valved line 28 into a flash still 30, where vaporization of readily vaporizable constituents is effected by reduction in pressure. The unvaporized material is discharged from the still 30 as fuel oil through a valved line 32 while the vapors are conducted through valved lines 34 and 36, a condenser 38, and a line 40, into a receiver 42. The condensate collected in receiver 42 may be used as the cooling fluid for cooling the vapors discharging through line 18, by withdrawing the condensate through the valved line 20 which is provided with a pump mounted therein. Any gas separated out in receiver 42 may be released through a valved line 44, and any excess condensate may be discharged through a valved line 46. Instead of vaporizing the liquid collected in the separator 24, it may be passed directly through lines 28, 36, the cooler 38, and the line 40, into the receiver 42, and reused as the cooling medium by forcing it again through the line 20, excess liquid being withdrawn through the valved line 46.

The vapors separated out in the separator 24, and including the gas produced in the conversion operation, together with the mixture of aromatic and olefin hydrocarbons, the major portion of which will normally boil below about 500° F., are conducted through a valved line 48 into the upper portion of a catalytic reaction chamber 50, and then downwardly through the chamber in intimate contact with a body of catalytic material adapted to effect the alkylation of the aromatic hydrocarbons contained in the mixture of vapors, as well as dehydrogenation and cyclization of olefins. The aromatic hydrocarbons are alkylated by the gaseous olefinic hydrocarbons as well as by some paraffinic hydrocarbons, due to the influence of the catalyst, so that side chain aromatic compounds are produced. The aromatic hydrocarbons in the vapors in the line 48 comprise benzene derivatives which may contain some side chains. The alkylation may alkylate at one or more positions in the benzene ring, so that a variety of side chain benzene and cyclic hydrocarbon derivatives are formed.

Dehydrogenation and cyclization of olefines containing six or more carbon atoms also occurs and the hydrogen will normally be consumed as fast as formed because of nascent and reactive conditions in the presence of the catalyst.

The catalyst used in the chamber 50 may comprise one of the catalytic materials referred to above, deposited for example, on clay or some inert carrier material supported in the chamber 50. The reaction is preferably carried out at relatively low temperatures, for example, of the order of from 600° to 800° F. and preferably while the vapors introduced through the line 48 are continuously maintained in the vapor state. The catalyzed reaction products from chamber 50 are withdrawn through a line 52 in which the products may be cooled, if desired, by introducing a cooling fluid through a valved line 54. This cooling is effected when the separation of the heavier polymerization products as a separate fraction is desired, or when a light colored distillable fraction is desired at the bottom of fractionating tower 52. In any case the products conducted through the line 52 may be discharged directly into a vapor separator 56 for the separation of any

heavier liquid constituents which are withdrawn through a valved line 58. The remaining vapors and gases are conducted from the separator 56 through a vapor line 60 into a fractionating tower 62 for the fractional separation of the hydrocarbons of lower boiling point produced by the process. If desired, the separator 56 may be entirely omitted and the vapors from the chamber 58 passed directly into the tower 62.

In the tower 62 the vapors are subjected to rectifying conditions, so that a rectified higher boiling product is obtained at the bottom of the tower and withdrawn through a valved line 64, and an overhead vapor fraction is obtained which is withdrawn through a valved line 66, subjected to condensing conditions in a condenser 68 mounted therein, and then conducted into a receiver 70. The vapor separator 56 may be omitted if the lower portion of the tower 62 is used to remove the heavier polymers, and the light colored reflux is removed as a side stream through line 78. Any of the unreacted gases produced by the process pass with the vapors from the tower 62 and are eventually separated out in the receiver 70. These gases, comprised primarily of saturated hydrocarbons, such as methane, ethane and propane, are discharged through an automatic pressure valve controlled line 72. In carrying out the rectification in the tower 62, a suitable reflux ratio is maintained therein by returning condensate from the receiver 70 through a line 74 by means of a pump mounted therein, so as to produce a distillate boiling preferably below 450° F. The overhead product produced by the rectification is withdrawn from the receiver 70 through a valved line 76, and if desired, an intermediate product may be produced on the tower and withdrawn from any desired level therein as a side stream, as for example, through a valved line 78.

The product removed through the line 76 is ordinarily passed to a stabilizer (not shown) and may have a boiling range of from about 70° F. to 350° F. or 400° F., and that withdrawn through the line 64, a boiling range of from 425° to about 550° F.

The improved process of the present invention may be carried out in slightly modified manner by utilizing the apparatus shown in Figs. 2 and 3 of the drawings, which apparatus includes certain elements which are identical with those used in Fig. 1. In describing the process in connection with Fig. 2, therefore, the apparatus elements which are the same as those shown in Fig. 1 will be referred to by the same reference characters.

In accordance with the modification of the process shown in Fig. 2, the oil to be converted is subjected to substantially the same treatment in the furnace 12 as that described in connection with Fig. 1, the oil being introduced through the pipe 2 and passed in series through the tube banks 4, 6, 8 and 10. In the modified process, however, the products discharged through the transfer line 14 at a temperature of from 980° to 1020° F. and at a pressure of approximately 250 lbs. per square inch, are conducted through a reaction coil 80 mounted in a temperature controlled chamber in which the temperature is controlled by supplying suitable tempering hot gases, for example, from the furnace 12, to maintain the temperature, or not permit it to rise above approximately 1070° F. at the outlet. In the formation of aromatic hydrocarbons in the tube bank 10 and reaction coil 80, sufficient time is permitted to secure approximately 45% of olefinic and 35% of aromatic hydrocarbons in the condensate portion

of the reaction products boiling below approximately 450° F. The exact temperature and pressure conditions necessary for securing approximately this conversion for any particular stock 5 are readily determinable by conducting an experimental operation on any given cracking furnace and reaction coil, and correlating the gravity of the product with its hydrocarbon analysis.

The highly heated reaction products resulting 10 from the treatment in the coil 80 are conducted through a line 82 into a line 22 in which the temperature of the products is suddenly reduced to a point below coke deposition in the line by introducing a cooling fluid into the vapor stream from 15 a valved line 20. The resulting mixture of the cooled products preferably at a temperature of from 600° to 800° F. are discharged into a separator 24 where vapors are separated and the resulting liquid removed and treated in the same manner as that described in connection with Fig. 1.

The vapors separated in the separator 24 of Fig. 2 and comprising constituents boiling up to a temperature of about 750° F., including any normally gaseous constituents formed by the conversion reactions carried out in the furnace 12 and coil 80, are conducted through a line 84 to a catalytic reaction zone comprising a coil 86. A finely divided catalyst such as one of the catalysts 30 referred to above, which may be deposited on a solid carrier and contained in a supply bin 88, is permitted to flow through a valved line 90 in which is mounted a rotary feed and measuring valve 92. This material is discharged at a controlled rate into the stream of vapors passing through the line 84 and carried through the reaction coil 86.

The rotary valve 92 may be of any suitable type 40 commonly used for feeding solids at a controlled rate. For example, this valve may comprise a rotary plug 94 provided with a pocket 96 for receiving the catalytic material from the bin 88 through the line 90. At every rotation of the plug 94, the material deposited in the pocket 96, 45 while in the position shown in Fig. 3, is discharged through the lower portion of the line 90 into the vapors in the line 84. The valve is preferably vapor-tight and provided with a valved vent line 98 so that any vapor picked up by the pocket 96 from the lower portion of line 90 will be vented through the line 98 without disturbing the material flowing under atmospheric pressure through the upper portion of the line 90. For more uniform distribution of catalyst in the 50 vapor stream, the plug preferably contains a number of pockets spaced around the circumference of the plug.

The vapor stream passed through the line 84 with approximately 3% by weight of suspended 60 catalytic material adapted to cause cyclization of olefins and alkylation of the aromatic hydrocarbons contained in the vapors, is passed through the coil 86 and subjected to a mild heating or cooling operation, so that the vapor and catalyst mixture are maintained at a temperature of about 700° F. and held at this temperature in the coil for a sufficient time to effect the desired alkylation reactions. In both forms of the process, it is desirable to utilize substantially all of the available gaseous olefinic type hydrocarbons for the alkylation of the aromatic hydrocarbons in order to reduce the amount of fixed gas vented from the 65 process.

The reaction products in vapor form and con-

taining the suspended catalytic material are discharged from the reaction coil 88 through a line 108 into a cyclone separator 102 which may be of any usual form, but adapted to withstand relatively high pressures, and in which the suspended solid catalytic material is separated. The solid catalyst is removed from the cyclone separator through a valved line 104 in which is mounted a rotary valve 106 which may be of substantially identical structure to that of the valve 82.

The cyclone separator 102 is preferably heavily insulated so that no condensation is permitted. The separated vapors are discharged from this cyclone separator through a line 52 and thereafter handled in the same manner as that described in connection with Fig. 1 of the drawings.

The catalytic material discharged through the line 104 may be revivified and reused by returning it to the bin or hopper 88. In the form of operation described in connection with Fig. 1, two or more catalyst chambers 88 may be used alternately, so that the one cut of the system may be connected to certain equipment for revivifying the catalyst, after which the chamber may be cut back into the system and reused.

In carrying out the improved process, the vapors and gases conducted from the separator 24 normally contain a major portion of hydrocarbons boiling below approximately 400° F. which is removed as an overhead product from the tower 62 since the aromatic hydrocarbons boiling within this range, after alkylation by the catalytic reaction, have the widest field of utility. For example, the alkylated benzene derivatives containing one or more side chains of from 1 to 4 carbon atoms, are particularly desirable for use as blending agents for increasing the anti-knock value of motor fuels. However, the vapor products discharged from the separator 24 also include higher boiling hydrocarbons which will include aromatic and cyclic compounds of a more complex nature than the simple benzene derivatives, i. e. naphthalene and anthracene derivatives. Such compounds after being alkylated, are valuable for use as intermediates in the manufacture of dyes and for many other purposes.

The products produced in accordance with the improved process of the present invention by the catalytic reaction, are preferably fractionated into rather narrow fractions and in some cases by close fractionation, so that individual aromatic hydrocarbons may be recovered for particular purposes. The fractionation operation may be controlled so that a product boiling within the range suitable for motor fuel, is withdrawn through the line 76. When the operation has been carried out so that approximately 45% of olefinic and 35% of aromatic hydrocarbons is contained in the condensable portion of the vapor stream boiling below 400° F., removed from the separator 24, the product boiling below approximately 400° F. and removed through the line 76 will contain approximately 85% of aromatic hydrocarbons comprised primarily of benzene derivatives containing one or more side chains.

A specific example of a typical operation in which a light straight run gas oil is introduced into the apparatus through the line 2, and subjected to the improved process is as follows:

Light gas oil is heated in the furnace 12 to a discharge temperature of 985° F. These vapors are then conducted to an enlarged reaction chamber at 225 pounds pressure such as the chamber 16, where an exothermic reaction of intermediate

degree is permitted to take place, the vapors being discharged from the chamber at a temperature of 1025° F., and instantaneously cooled to 750° F. The vapors remaining after this cooling, and at a temperature of about 750° F. and 65 pounds pressure, are conducted through a body of a catalyst comprising a calcined mixture of phosphoric acid, and adsorptive clay, with 3% of molybdenum sub-oxides. The vapor mixture discharged from the catalytic chamber is passed directly to a fractionating tower in which they are fractionated to take overhead, constituents boiling up to a temperature of about 375° F. The resulting condensed overhead product with boiling range of from 87° F. to 405° F., contains 83% of aromatic hydrocarbons as determined by the Egloff and Morrell method (Industrial & Engineering Chemistry, vol. 18 (1926) pages 354-356). The heavy material removed from the bottom of the tower comprises approximately 10% of the original charging stock, while the product collected overhead, as referred to above, comprises approximately 50% of the original charging stock to the furnace.

The gas loss on the whole operation is about 15-20% as compared to from 30% to 40% gas loss previously encountered in the manufacture of products containing high percentages of aromatic compounds.

From the foregoing description, it is apparent that various modifications and alterations may be made in the process without departing from the spirit and scope of the invention, as defined by the accompanying claims.

Having thus described the invention in its preferred form, what is claimed as new is:

1. The process of manufacturing side chain cyclic and aromatic hydrocarbons from petroleum oil distillates of substantially paraffinic character, which comprises passing the petroleum distillate charging stock through a heating zone in a confined stream of restricted cross-section and therein heating the distillate to a temperature of from 950° to 1020° F., thereafter subjecting the heated distillate to an exothermic reaction at a high temperature for a substantial period of time during which the distillate is converted into a reaction mixture containing a substantial proportion of condensable products boiling below 400° F., said proportion containing from approximately 35% to approximately 55% of olefinic hydrocarbons and from approximately 30% to approximately 45% of aromatic hydrocarbons, cooling the resulting mixture of conversion products to condense high boiling components thereof, but insufficiently to condense the constituents boiling up to approximately 500° F., separating the condensed materials from the resulting vapors and gases and passing the latter directly into a catalytic reaction zone in intimate contact with a solid alkylation and cyclization catalyst, maintaining a reaction temperature upwards of about 600° F. in said catalytic reaction zone which is sufficient to convert the vapors and gases into the desired cyclic and aromatic hydrocarbons, and fractionating the resulting reaction products to recover the desired hydrocarbons therefrom.

2. In the process of manufacturing side chain cyclic and aromatic hydrocarbons in which an olefinic, cyclic and aromatic hydrocarbon stock is subjected to alkylation conditions in the presence of an alkylation catalyst, the improvement which comprises preparing a hydrocarbon stock for alkylation by cracking a mineral oil distillate at a temperature of from 950° to 1020° F. under

conversion conditions adapted to produce a substantial proportion of condensable material boiling below a temperature of from 400° to 450° F., said material containing from approximately 35% to approximately 55% of olefinic hydrocarbons and from approximately 30% to approximately 45% of cyclic and aromatic hydrocarbons, subjecting the highly heated products of the cracking operation to cooling sufficient to condense constituents boiling above about 500° F. and leave a vapor fraction including said condensable material and the normally gaseous hydrocarbons produced by the cracking operation, separating said vapor fraction from said condensed constituents as said hydrocarbon stock, and passing said vapor fraction while hot directly into an alkylation zone in intimate contact with a solid alkylation catalyst at a temperature of from 600° to 800° F. to produce said side chain cyclic and aromatic hydrocarbons.

3. In the process of manufacturing side chain aromatic hydrocarbons in which a stock comprised of olefinic and aromatic hydrocarbons is subjected to alkylation conditions in the presence of an alkylation catalyst, the improvement which comprises preparing the hydrocarbon stock for alkylation by cracking a mineral oil distillate at a temperature of from 950° to 1020° F. under conversion conditions adapted to produce a substantial proportion of condensable material boiling below a temperature of from 400° to 450° F., said material containing at least 30% each of olefinic hydrocarbons and aromatic hydrocarbons, subjecting the highly heated products of the cracking operation to cooling sufficient to condense constituents boiling above about 500° F. and leave a vapor fraction including said condensable material and the normally gaseous hydrocarbons produced by the cracking operation,

separating said vapor fraction from said condensed constituents as said hydrocarbon stock, and passing said vapor fraction while hot directly into an alkylation zone in intimate contact with a solid alkylation catalyst at a temperature of from 600° to 800° F. to produce said side chain aromatic hydrocarbons.

4. In the process of manufacturing side chain cyclic hydrocarbons and aromatic hydrocarbons 10 in which a stock comprised of olefinic and aromatic hydrocarbons is subjected to alkylation and aromatization conditions in the presence of an alkylation and aromatization catalyst, the improvement which comprises preparing the hydrocarbon stock for the operation by cracking a mineral oil distillate at a temperature of from 950° to 1020° F. under conversion conditions including an aromatic-forming exothermic reaction, stopping the exothermic reaction when the condensable material in the reaction product boiling below a temperature of from 400° to 450° F. contains approximately but not more than approximately 35% of aromatic hydrocarbons, subjecting the heated products of the cracking operation to cooling sufficient to condense constituents boiling above about 500° F. and leave a vapor fraction including said condensable material and the normally gaseous hydrocarbons produced by the cracking operation, separating said vapor fraction from said condensed constituents as said hydrocarbon stock, and passing said vapor fraction while hot directly into a reaction zone in intimate contact with a solid alkylation and aromatization catalyst at a temperature upwards of about 600° F. to produce said side chain cyclic hydrocarbons and aromatic hydrocarbons and to substantially increase the quantity of aromatic hydrocarbons over the quantity contained in said stock.

WILLIAM KAPLAN.
